UNITED STATES PATENT OFFICE.

ALBERT B. SCHOFIELD, OF BROOKLYN, NEW YORK, ASSIGNOR TO
KEYSTONE SEAL & PRESS COMPANY, OF NEW YORK, N. Y., A
CORPORATION OF NEW JERSEY.

SEAL-PRESS.

SPECIFICATION forming part of Letters Patent No. 691,079, dated January 14, 1902.

Application filed July 13, 1901. Serial No. 68,140. (No model.)

To all whom it may concern:

Be it known that I, ALBERT B. SCHOFIELD, a citizen of the United States, and a resident of the borough of Brooklyn, in the city and State of New York, have invented a new and useful Seal-Press, of which the following is a specification.

My invention relates to a seal-press, and more particularly to a seal-press intended to be operated by the hand for spreading the end of a soft-metal rivet and forming thereon a letter or symbol, one or more, for identifying the seal and the car or other vehicle or package sealed.

15 A practical embodiment of my invention is represented in the accompanying drawings, in which—

Figure 1 is a view of the press as it appears when opened to receive the soft-metal rivet between its jaws. Fig. 2 is a longitudinal section of the same. Fig. 3 is a longitudinal section showing the parts closed in the position which they assume when the compression or upsetting of the head of the rivet has been completed; and Fig. 4 is a view in detail of the die-holder, showing the die formed integral with its holder as distinguished from removable therefrom, as represented in the other figures.

30 The press comprises three main parts—viz., the lower jaw, the upper jaw, and the die-holder—together with the means for assembling them—in the present instance rivets—and an antifriction-roller interposed between the upper jaw and the die-holder.

The lower jaw is denoted by *a* and is preferably extended to form a trough-like handle portion *b* for rendering it light and at the same time forming a seat between its side walls for the reception of the die-holder housed therein. The lower jaw *a* is provided with a depression *c*, intended to receive the head of the soft-metal rivet to be operated upon, and so located as to coact with the die in the die-holder.

45 Access to the parts from the side, as well as the front, is obtained through a cut-away portion *d* in the front of the sides of the jaw *a*, and the said sides are extended upwardly at their forward ends to receive the pivot *e*, by

which the upper jaw is secured between the sides of the lower jaw.

The upper jaw is denoted by *f* and is extended to form a handle portion *g*. It is, as before stated, pivoted between the sides of the lower jaw at *e*, preferably by means of a rivet, to secure it permanently in place and carries at the lower portion of its head an antifriction-roller *h*, which is intended to roll along the top of the die-holder in a direction toward the free or die end of the holder as the handle *g* is swung toward the handle *b* to force the die-holder and die toward the rivet-receiving depression *c*.

55 The die-holder comprises a rigid bar *i*, of suitable strong material, pivotally connected between the sides of the handle portions *b* of the lower jaw, preferably by means of a rivet *j*. The pivotal point of the bar *i* is located as far as practicable from the die to 70 reduce the curvature of the arc in which its free end swings, so that it may approach the stationary jaw substantially parallel therewith.

75 The free end of the die-holder carries the die *k* in position directly above the depression *c* in the lower jaw. The die *k* may be removably connected to the end of the bar *i* by means of a set-screw *l* or other suitable die-retaining means, or the die may be formed 80 integral with the die-holder, as shown at *k'*, Fig. 4.

The back of the die-holder is provided with a pronounced upward incline *m*, terminating in a horizontal portion *n* as the jaw *g* approaches the position to bring its roller *h* "on center" with respect to its pivotal connection with the jaw *a*.

85 The die-holder is lifted away from the depression *c* in the lower jaw, carrying with it 90 the upper jaw into position to receive a rivet by means of a spring *o*, preferably a spiral spring, seated within a socket *p* in the lower jaw and bearing at its upper end against the under side of the die-holder *i*.

95 In operation the soft-metal rivet which is to form the seal having been inserted with its head in the depression *c* and its opposite end beneath the die *k* or *k'* the handle *g* is forced toward the handle *b*. In the early part 10

of the movement the roller *h* will ride up the incline *m* and rapidly throw the free end of the die-holder, with the die thereon, toward the depression *c*, rapidly upsetting the free end 5 of the rivet, and as the compression or upsetting approaches its completion the roller *h* will ride along the level portion *n* in proximity to the incline *m* just as it approaches the position of on center with respect to 10 the pivotal connection of the jaw *f* with the jaw *a*, thereby producing a very powerful pressure upon the die-holder and causing the letter or symbol or several of them to be very distinctly raised from or formed on the upset 15 portion of the rivet.

The press is an exceedingly simple one and has great power and capacity in proportion to the distance through which the handles swing away from and toward each other.

20 To prevent the handle *g* from being opened too far, its nose *q* is so shaped that it will impinge against the top of the die-holder when the jaw has reached its full open position, and to prevent the roller *h* from being thrown 25 completely onto or past center, so as to render the spring *o* of no avail in returning the jaw, a stop *r* is provided, in the present instance depending from the under side of the handle *g* in position to engage the die-holder *i* near 30 its pivotal connection with the jaw when the handles have been closed as far as desirable.

The die *k* may be readily removed from its position by loosening the set-screw *l* in the event a removable die is used in the place of 35 the stationary die referred to in Fig. 4.

It is obvious that changes might be resorted to in the form and arrangement of the several parts without departing from the spirit and scope of my invention. Hence I do not

wish to limit myself strictly to the structure 40 herein set forth; but

What I claim is—

1. A seal-press comprising a die-jaw terminating in a handle portion, a rigid die-holder bar pivoted at one end to the handle portion 45 of said die-jaw with its die-carrying end free to swing toward and away from the die in said jaw, and an operating-jaw pivoted to the die-jaw and terminating in a handle portion, the said operating-jaw being provided with a cam 50 arranged to travel along the swinging die-holder toward its die-carrying end as the compression progresses, substantially as set forth.

2. A seal-press comprising a die-jaw terminating in a handle portion, an operating-jaw 55 pivoted to said die-jaw and terminating in a handle portion, a die-holder bar arranged to swing between said jaws, the said operating-jaw being provided with a cam arranged to engage the swinging die-holder, and the said 60 swinging die-holder being provided with a pronounced incline with which the said cam engages during the initial compression movement to cause the dies to rapidly approach each other, and with a bearing-surface at an 65 angle to said pronounced incline along which the cam travels during the final compressing movement to cause the dies to approach each other more slowly, substantially as set forth.

In testimony that I claim the foregoing as 70 my invention I have signed my name, in presence of two witnesses, this 26th day of June, 1901.

ALBERT B. SCHOFIELD.
